CLAIM

The ornamental design for a battery caddie as shown and described.

DESCRIPTION

FIG. 1 is a front perspective view of a battery caddie, according to the present invention;

FIG. 2 is a rear perspective view of the battery caddie of FIG. 1;

FIG. 3 is a right side elevational view of the battery caddie of FIG. 1;

FIG. 4 is a left side elevational view of the battery caddie of FIG. 1;

FIG. 5 is a rear elevational view of the battery caddie of FIG. 1;

FIG. 6 is a front elevational view of the battery caddie of FIG. 1;

FIG. 7 is a top plan view of the battery caddie of FIG. 1; and, FIG. 8 is a bottom plan view of the battery caddie of FIG. 1.

The dashed broken lines in the Figures illustrate portions of the battery caddie and do not form part of the claimed design.
